UNITED STATES PATENT OFFICE.

WINSLOW ALLDERDICE, OF WARREN, OHIO, ASSIGNOR TO WILLIAM H. ALLDERDICE, OF WASHINGTON, DISTRICT OF COLUMBIA.

WATER PURIFIER AND COOLER.

SPECIFICATION forming part of Letters Patent No. 497,743, dated May 16, 1893.

Application filed December 8, 1892. Serial No. 454,478. (No model.)

To all whom it may concern:

Be it known that I, WINSLOW ALLDERDICE, a citizen of the United States, residing at Warren, in the county of Trumbull and State of Ohio, have invented certain new and useful Improvements in Water Purifiers and Coolers; and I do hereby declare the following to be a full, clear, and exact description of the invention, such as will enable others skilled in the art to which it appertains to make and use the same.

My invention relates to improvements in water purifiers and coolers, and it consists of certain novel features hereinafter described and claimed.

Reference is had to the accompanying drawings, in which the same parts are indicated by the same letters throughout the several views.

Figure 1 represents a plan view of the water purifier and cooler with the covering plate removed. Fig. 2 represents a central vertical section of the device shown in Fig. 1.

A represents the inlet pipe connected to a hydrant or other water supply where a sufficient head of water is provided. A⁰ represents an enlargement of the said pipe forming a valve seat for the valve or cock B. Beyond this valve seat are two passages for the water A' and A² separated from each other by the partition a and opening into the passages A³ and A⁴ in a casting on either side of the filter C. Hollow screws D form a means of holding the filter in place, and at the same time provide channels for the passage of the water from the said passages A³ and A⁴ through the said filter; for this purpose, each of the said hollow screws is provided with two holes d opening into the interior of the hollow screw from the channels A³ and A⁴ respectively. Beyond the filter, the two channels for the water converge as at A⁵ and A⁶, but being still separated by the partition a', these channels open into the interior of the valve seat A⁷ provided with the three-way cock B' having ports b², b³ and b⁴ adapted to allow the water from the filter to flow either into the delivery pipe A⁸, or into the waste pipe E and drain F, shown in dotted lines in Fig. 2.

H represents a vessel suitably insulated,

and mounted on a pedestal H⁵. This vessel is provided with two chambers H' H², the latter containing the closed metallic ice box H³, and the former being surmounted with the heating dome H⁴.

The vessel H is preferably composed of an inclosing shell h a space h' filled with insulating material, or simply air, and an inner shell h². This vessel is surmounted by a dome-shaped cap h³ having air holes h⁴. h⁵ represents the cover of the vessel beneath the said cap, and h⁶ represents a water-tight partition separating the chambers H' and H².

h⁷ represents the roof of the box H³ which holds the ice I, and rests on feet h⁸, clear of the bottom of the chamber H².

h⁹ represents the door opening from the exterior into the ice box H³; and h¹⁰ represents a drain cock from the base of the said ice chamber for drawing off the melted ice.

The pipe k leads upward from the chamber H' into the heating coil K over the Bunsen burner L connected by the pipe L' to a suitable gas pipe. The heating coil K leads downward into the condensing and cooling coil K', which opens at its lower end by means of the pipe k' into the chamber H². k² represents a drain cock for the said chamber H². The chamber H² is provided with an overflow pipe M having a check valve m adapted to open outward but to remain normally closed.

The operation of the device is as follows:—The water coming from the hydrant by means of the pipe A passes through the valve B, the passage A', the upper hollow screw D, down through the filter C, the lower hollow screw, the passage A⁶, the ports b⁴ and b² in the valve B', and the inlet pipe A⁸ into the chamber H'. Rising in this chamber until it reaches the top thereof, it passes into the pipe k and the heating coil K, where the burning gas converts a portion of the water into steam and brings the whole of it to a sufficiently high temperature to kill all the germs that may be therein contained. From the heating coil K, the hot water and steam pass down through the condensing and cooling coil K', finally dripping into the chamber H² through the pipe k'. This chamber H² is the cooling chamber, the water therein being cooled by contact with the exterior of the metallic walls of the chamber H³.

containing the ice I. The water, after having been cooled may be drawn off by means of the faucet k^2 . It will be seen that in the chamber H^1 the inflowing water enters at the bottom and cools the lower portion of the condensing and cooling coil K' , while the water rising in the pipe k from the upper portion of said chamber has been already heated to a considerable extent by the hot water and steam 5 descending through the coil K' . In this way the water is gradually heated and is gradually cooled and advantage is taken of the natural convection currents which will occur. It will be seen that in the cooling chamber H^2 10 the water is not in contact with the ice, and is drawn from a contracted space in the lower portion of the chamber after having been in contact with the conducting walls of the ice chamber H^3 . It will be seen that the cold water 15 would naturally descend to the lower portion 20 of the vessel H^2 , at which position the faucet k^2 is placed.

In order that the water from the melting ice may be drawn off, a faucet from the lower 25 part of the ice chamber H^3 is provided.

The ice chamber H^3 is supported on legs h^3 so that the water in the chamber H^2 may flow beneath it, thus increasing the cooling surface.

Since the filter C will speedily become soiled 30 with the sedimentary matter found in ordinary hydrant water, it will become necessary to either change the filter frequently or to wash it out. I prefer to wash it out in the manner hereinafter described. Assuming 35 that the filter has been in use long enough to have become soiled, the cock B should be turned so that the ports b and b' should be turned so that the port b^2 may open into the passage A^4 , and the port b^3 into the waste pipe 40 E, the water will then flow from the pipe A into the passage A^4 through the filter upward, down through the passage A^5 and out of the waste pipe E, in this way the filter will be 45 thoroughly cleansed and when the wastewater shows sufficient clearness the cocks may be turned back into the position shown in Fig. 2, and the process of purifying the water may be resumed.

I do not claim any particular form of filter, 50 there being many well known in the art which could be satisfactorily used with the herein described device.

The supply of water admitted to the vessel H is controlled either by the valve B, or by 55 the valve B' ; and any excess of water admitted to the vessel H overflows through the valve m and pipe M. This valve readily opens outward for the overflow of the water or the egress of compressed air due to the filling of 60 the chamber H^2 , but it resists all pressure from the outside and hermetically closes the chamber H^2 to atmospheric impurities.

Having thus described my invention, what I claim, and desire to secure by Letters Patent 65 of the United States, is—

1. A water purifier, consisting of a vessel having an upper and a lower chamber therein,

a supply pipe admitting water into the lower portion of the upper chamber, a heating coil connected to the upper portion of said upper chamber, a surface condenser partly occupying said chamber connected to said heating coil and draining into said lower chamber, and a closed receptacle containing ice partly occupying said lower chamber, substantially as described.

2. A water purifier consisting of a vessel having an upper and a lower chamber therein, a supply pipe admitting water into the lower portion of the upper chamber, a heating coil connected to the upper portion of the said upper chamber a surface condenser partly occupying said upper chamber connected to said heating coil and draining into said lower chamber, a closed receptacle containing ice partly occupying said lower chamber, and an overflow pipe provided with a check valve opening outward placed at the upper part of said lower chamber, substantially as described.

3. A water purifier, consisting of a vessel having an upper and a lower chamber therein, a supply pipe admitting water into the lower portion of the upper chamber, a filter connected to said supply pipe, a heating coil connected to the upper portion of said upper chamber, a surface condenser partly occupying said chamber connected to said heating coil and draining into said lower chamber, and a closed receptacle containing ice partly occupying said lower chamber, substantially as described.

4. A water purifier consisting of a vessel having an upper and a lower chamber therein, a supply pipe admitting water into the lower portion of the upper chamber, a filter connected to said supply pipe, a heating coil connected to the upper portion of the said upper chamber, a surface condenser partly occupying said upper chamber connected to said heating coil and draining into said lower chamber, a closed receptacle containing ice partly occupying said lower chamber, and an overflow pipe provided with a check valve opening outward placed at the upper part of said lower chamber, substantially as described.

5. A water purifier, consisting of a vessel having two chambers therein, one above the other and separated by a water-tight partition, the upper chamber being for the distilling of the water and the lower for the reception of the distilled water, a supply pipe admitting water into the lower portion of the upper chamber, a heating coil connected to the upper portion of said upper chamber, a surface condenser partly occupying said chamber and draining into said lower chamber, and means for draining the water off from said lower chamber, substantially as 130 and for the purposes described.

6. A water purifier, consisting of a vessel having two chambers therein, one above the other and separated by a water-tight parti-

tion, the upper chamber being for the distilling of the water and the lower for the reception of the distilled water, a supply pipe admitting water into the lower portion of the upper chamber, a filter connected to said supply pipe, a heating coil connected to the upper portion of said upper chamber, a condensing coil partly occupying said chamber and draining into said lower chamber, and

means for draining the water off from said lower chamber, substantially as and for the purposes described.

In testimony whereof I affix my signature in presence of two witnesses.

WINSLOW ALDERDICE.
